METHOD AND APPARATUS FOR COATING TUBULAR ARTICLES

John E. Socke, Pelham Manor, N.Y., assignor to American Can Company, New York, N.Y., a corporation of New Jersey

Filed Mar. 10, 1958, Ser. No. 720,315

6 Claims. (Cl. 117—96)

The present invention relates to a method of and apparatus for coating interior surfaces of can bodies and the like and has particular reference to producing and utilizing a substantially flat 360 degree spray pattern to effect the coating operation.

The coating of the interior surfaces of can bodies and other hollow articles such as pipes etc., usually is effected by way of a spraying operation. In some cases the article to be sprayed is rotated while a spray nozzle is telescopically introduced into the article. This requires mechanism for rotating the article as well as mechanism for operating the nozzle. In such methods of spraying it is difficult to control the quantity of coating material applied to the article surface and this results in difficulty in obtaining a uniform thickness of film evenly distributed over the entire surface of the article.

An object of the instant invention is to effect a uniform coating of the entire interior surface of a can body or like article.

Another object is to produce a substantially flat 360 degree radial spray jet pattern to effect such a uniform coating of the interior of a can body or like article.

Another object is to produce such a spray jet pattern in a manner which permits of mixing in the pattern, the various material components so as to control the final composition of the coating film and to control the degree of atomizing action and the resultant distribution and thickness of the film.

Numerous other objects and advantages of the invention will be apparent as it is better understood from the following description, which, taken in connection with the accompanying drawings, discloses a preferred embodiment thereof.

Referring to the drawings:

Figure 1 is an end view of an apparatus embodying the instant invention and utilized for carrying out the steps of the method portion of the invention, parts being broken away and parts being shown in section;

Fig. 2 is a sectional view taken substantially along the broken line 2—2 in Fig. 1, with parts broken away;

Fig. 3 is a perspective schematic view illustrating certain of the parts in exploded relation;

Fig. 4 is an enlarged sectional view taken through a can body and showing how a substantially flat 360 degree radial spray jet pattern is produced and utilized to coat the interior surface of the body;

Figs. 5 to 9 inclusive are schematic views of a can body and spray nozzles, and illustrating the various stages of forming the spray jet pattern and coating the body; and

Fig. 10 is a vertical sectional view taken on line 10—10 of Fig. 4.

As a preferred and exemplary embodiment of the instant invention the drawings illustrate method steps of and apparatus for coating the interior surface of a cylindrical can body A (Figs. 1 and 4) with a protecting film B applied uniformly over the entire surface by a substantially flat 360 degree radial spray jet pattern C.

2

In accordance with the method steps of the instant invention the 360 degree radial spray jet pattern C is created by providing a pair of spray jets D discharged from a pair of movable nozzles E, F and directing the jets toward each other in closely spaced and axially aligned relation to effect impingement or collision of the jets and a resulting outward deflection at right angles to the axes of the jets. This outward deflection results in a substantially flat 360 degree spray pattern C.

Upon formation of the spray pattern C, relative longitudinal telescopic movement is effected between the can body and the spray pattern, along the axis of the can body to project the coating material components in the spray pattern against the interior surface of the can body to produce the uniform, evenly distributed protective film B.

As illustrated in Figs. 5 to 9, inclusive, the two oppositely disposed nozzles E, F normally are located adjacent the open ends of the can body A to be coated and one of the nozzles, for example nozzle E, is projected through the body along its axis to a position closely adjacent and in axial alignment with the other nozzle, for example the nozzle F, as shown in Fig. 6. With the two nozzles in this position, the coating material components to be sprayed onto the can body, are discharged from the nozzles with the result that the two issuing jets D collide and produce the spray pattern C as mentioned above.

While the two nozzles E, F remain in this relative spray pattern forming position, they move together, back through the can body along its axis as shown in Fig. 7, or as an alternate method the can body is moved forward over the nozzles while the latter remain stationary, to project the coating material progressively and evenly over the entire inner surface of the body. When the nozzles reach the opposite end of the body as shown in Fig. 8, the coating material components are cut off and the spray pattern C is thus dissipated. The spray nozzle F then moves back through the body to its original position, leaving the nozzle E at the opposite end of the body, in its original position, thus terminating the coating operation and leaving the body with its interior surface entirely and uniformly coated.

The coating material components hereinbefore mentioned preferably are the coating material itself and a propellant such as compressed air or other fluid pressure medium. Both components, the material and the propellant may be discharged from each of the nozzles E, F to combine to produce the spray pattern C, or if desired, the coating material may be discharged from one nozzle and the propellant from the other nozzle so that they mix in the spray pattern C. In another combination two different kinds of coating material and propellant may be discharged from the nozzles so as to mix in the spray pattern C and be applied to the can body in their mixed state to produce the coating film.

In such a method of coating the interior surfaces of can bodies, the collision of the two jets D of coating material components to produce the spray pattern C, has the effect of finely atomizing the coating materials and thereby facilitates the application of the material to the bodies in a uniform thickness film which is evenly distributed over the entire surface.

In the apparatus portion of the invention Figs. 1, 2 and 3 illustrate one form of machine for carrying out the above explained method steps. In this apparatus the can bodies A to be interiorly coated preferably roll down on inclined chute 21 (Fig. 2) in processional order and are picked off individually by pockets 22 in a rotatable turret 23 mounted on a horizontal shaft 24 carried in a pair of spaced bearings 25 of a main frame 26 (see also Fig. 1).

The turret 23, through its shaft 24 is rotated intermitt-

tently, in a clockwise direction as viewed in Fig. 2, to carry a picked-up can body A from the chute 21 to a coating station X, then advance it to an idle station Y, and then carry it to a discharge station Z where the body coated at station X is discharged into a chute 28 for delivery to any suitable place of deposit. A guide rail 29 disposed adjacent the periphery of the turret 23 retains the bodies in their pockets 22 during this travel.

Intermittent rotation of the turret 23 preferably is effected by a conventional indexing device which includes an interrupted thread indexing cam 31 mounted on a continuously rotating shaft 32 journaled in bearings 33 in the main frame 26. The shaft is rotated in any suitable manner. With each rotation of the cam shaft 32, the indexing cam 31 engages one of a plurality of rollers 35 mounted on the turret 23 in spaced relation around the turret, and thereby rotates the turret 23 through one step of rotation in the conventional manner.

At the coating station X, the two spray nozzles E, F, hereinbefore mentioned, are located on opposite sides of the path of travel of the can bodies into and out of the station. The nozzles preferably are disposed in a horizontal position for horizontal movement and are axially aligned with each other and with the axis of a can body A brought to rest by the turret 23 at the coating station.

Each of the nozzles E, F are provided with a horizontally disposed discharge orifice 37 (Figs. 1 and 2). The nozzles are mounted on the inner ends of opposed horizontal feed tubes 38 carried in slide bearings 39 on brackets 41 projecting up from the turret shaft bearings 25. The feed tubes 38 are connected by flexible coating material pipes 43 and fluid pressure pipes 44, to respective normally closed cut-off valves 45, 46 (see Fig. 3) actuated by a normally deenergized electric solenoid 47. The solenoid 47 is energized at the proper time as will be hereinafter explained by the closing of a normally open cam actuated electric switch 48 which connects the solenoid with a suitable source of electric current such as a generator 49. The valve 45 is connected by a pipe 51 to a suitable source of supply of the coating material, while the valve 46 is connected by a pipe 52 to a source of compressed air or other suitable fluid pressure medium.

The outer ends of the nozzle feed tubes 38 are connected to piston rods 53, 54 (Figs. 1 and 3) which carry respective pistons 55, 56 which operate in respective opposed fluid pressure cylinders 57, 58 mounted on the brackets 41. Fluid pressure, for example compressed air, is introduced into the cylinders to reciprocate the pistons and hence the nozzles E, F in the proper direction and in timed relation to bring about the formation of the spray jet pattern C and to apply the coating material to the interior surface of the can body as hereinbefore explained.

Introduction of compressed air into the cylinders 57, 58 is controlled by a rotary valve comprising a pair of rotatable discs 61, 62 (Figs. 2 and 3) secured to and rotating with the indexing cam shaft 32 and a set of three cooperating stationary valve blocks 63, 64, 65 which surround the shaft 32 but which are held stationary by a bolt 66 secured to the adjacent bearing bracket 33 (see Fig. 2). The valve disc 61 is interposed between the stationary valve blocks 63, 64, while the disc 62 is interposed between the blocks 64, 65 as shown in Fig. 2.

The stationary valve block 63 carries two pipes 71, 72 which lead to and connect with the outer and the inner ends respectively of the cylinder 57 which controls reciprocation of nozzle E. In a similar manner the stationary valve block 65 carries two pipes 73, 74 which lead to and connect with the outer and inner ends respectively of the cylinder 58 which controls reciprocation of nozzle F. The ends of these pipes 71, 72, 73, 74 in the blocks 63, 65 are connected, in sequence and at the proper time, with a source of fluid pressure connected by a pipe 75 (Fig. 2) to a recess 76 in the middle stationary valve block 64 (Fig. 3). For this purpose, the valve disc 61 is formed with slot ports 77, 78 which are registerable with the

pipes 71, 72 respectively, in the block 63 and with ports 79, 80 in the block 64. Vent ports 82, 83 are also provided in the disc 61.

In a similar manner the valve disc 62 is formed with slot ports 85, 86 which are registerable with the pipes 73, 74 respectively, in the block 65 and with ports 87, 88 in the middle block 64. This disc also is provided with vent ports 89, 90 and on its outer periphery is also provided with a cam 92 for the operation of the solenoid switch 48 hereinbefore mentioned.

In operation, the valve discs 61, 62 rotate continuously with the indexing cam shaft 32. During 180 degrees of each revolution of this shaft 32, the indexing cam 31 is rotating the turret 23 through a partial rotation which advances a can body A into the coating station X. During the remaining 180 degree revolution of the shaft 32, the turret remains stationary to hold the can at the coating station. At the beginning of this remaining 180 degree revolution of the shaft 32, the slot port 77 in the valve disc 61 registers with the port 79 in valve block 64 and simultaneously registers with pipe 71 in block 63 to introduce compressed air from pipe 75 and recess 76 of block 64 into the outer end of the cylinder 57 to push the nozzle E through the can body at station X and to advance it into closely spaced relation to nozzle F as shown in Fig. 6. During this operation, air within the cylinder 57 ahead of its piston, is vented through the pipe 72 to the vent port 83 in disc 61 and thus to the outside atmosphere.

While the nozzle E is momentarily held in this position adjacent the nozzle F, the cam 92 on the valve disc 62 engages and closes the electric switch 48. This energizes the solenoid 47 and through its energization opens the coating material valve 45 and its cooperating air valve 46, to effect discharge of the spray jets D from both nozzles E, F and to thereby create the substantially flat 360-degree radial spray pattern C hereinbefore explained. The spray pattern thus formed is free from obstruction by any tubes or other parts passing through the spray.

Immediately following creation of the spray pattern C, slot port 77 in valve disc 61 moves out of register with port 79 in block 64 and pipe 71 in block 63 to cut off the air to the outer end of cylinder 57. This is immediately followed by two actions as follows. Slot port 78 in valve disc 61 moves into register with port 80 in block 64 and pipe 72 in block 63 to feed air into the inner end of cylinder 57, and slot port 85 in valve disc 62 moves into register with port 87 in block 64 and pipe 73 in block 65 to feed air into the outer end of cylinder 58. Thus the air entering the opposite ends of the two cylinders 57, 58 simultaneously, shifts the two nozzles E, F back through the can body A while maintaining them in their relative closely spaced relation to preserve the spray pattern C as shown in Fig. 7. This back travel of the nozzles E, F effects the interior coating of the can body as hereinbefore explained. During this back travel the cylinder 57 is vented through its pipe 71 and vent port 82 in valve disc 61 and the cylinder 58 is vented through its pipe 74 and vent port 90 in valve disc 62.

Upon completion of this back travel or coating stroke, when the nozzle E reaches its original position as shown in Fig. 8, the cam 92 on the valve disc 62 rides off the switch 48 and thereby permits it to open. This deenergizes the solenoid 47 and thus effects closing of the coating material valve 45 and its air valve 46 and thereby cuts off and dissipates the spray pattern C. This is immediately followed by a return of the nozzle F to its original position as shown in Fig. 9. For this purpose the slot ports 78, 85 in their respective valve discs 61, 62 move out of register with the ports 80, 87 in the block 64 and the pipes 72, 73 in the blocks 63, 65 to cut off the air from the cylinders 57, 58. This is immediately followed by the slot port 86 in valve disc 62 rotating into register with the port 88 in the block 64 and the pipe 74 in the block 65. This permits air to flow into the inner

end of the cylinder 58 and thereby returns the nozzle F to its original position. During this return stroke, the outer end of the cylinder 58 is vented through the pipe 73 and the vent port 89 in the valve disc 62. This completes the cycle of the coating operation.

It is thought that the invention and many of its attendant advantages will be understood from the foregoing description, and it will be apparent that various changes may be made in the form, construction, and arrangement of parts of the apparatus mentioned herein and in the steps and their order of accomplishment of the method described herein, without departing from the spirit and scope of the invention or sacrificing all of its material advantages, the apparatus and method hereinbefore described being merely a preferred embodiment thereof.

I claim:

1. The method of interiorly coating can bodies and the like, comprising positioning an open-ended tubular can body between a pair of axially aligned and spaced spray nozzles disposed concentric to said body, effecting relative movement between said body and one of said nozzles to dispose the latter in close axially spaced relation to the other nozzle, effecting relative movement between said body and both of said nozzles in the reverse direction while discharging sprays of fluid coating material under pressure from the nozzles for impingement of said sprays against one another and resulting outward deflection of the sprays in a substantially flat 360° radial spray pattern disposed at right angles to the nozzle axes, whereby to completely interiorly coat the can body during relative movement of said body and nozzles.

2. The method of interiorly coating can bodies and the like, comprising positioning an open-ended tubular can body between a pair of axially aligned and spaced spray nozzles disposed concentric to said body, moving one of said nozzles through said body into close axially spaced relation with the other nozzle, simultaneously moving both of said closely spaced nozzles in the reverse direction through said body while discharging sprays of fluid coating material under pressure from the nozzles for impingement of said sprays against one another and consequent resulting outward deflection of the sprays in a substantially flat 360° radial spray pattern disposed at right angles to the nozzle axes, whereby to completely interiorly coat the can body during reverse unitary movement of said nozzles through said body, and finally axially withdrawing one of said nozzles from said body for discharge of the coated can body from between the nozzles and positioning an uncoated can body between said nozzles for a similar coating operation thereon.

3. Apparatus for interiorly coating can bodies and the like, comprising an intermittently rotatable turret having peripheral pockets for receiving and advancing the cans to a coating station, a pair of horizontal axially aligned and spaced spray nozzles at said station for receiving an open-ended tubular can body therebetween, fluid pressure means for effecting relative axial reciprocation between said nozzles independently and in unison and said can body while the latter is at rest at said station to vary the degree of axial spacing of the nozzles, and means for discharging fluid coating material under pressure in opposed spray jets from said nozzles simultaneously while the nozzles are disposed in close axially spaced relation to effect impingement of said jets against one another and outward deflection thereof in a substantially flat 360° radial spray pattern disposed at right angles to the axes of said nozzles for projection of said pattern against the interior surface of the can body to completely coat the same during unitary axial movement of said nozzles relative thereto.

4. Apparatus for interiorly coating can bodies and the like, comprising an intermittently rotatable turret having peripheral pockets for receiving and advancing the cans to a coating station, a pair of horizontal axially aligned and spaced spray nozzles at said station for receiving an

open-ended tubular can body therebetween, fluid pressure means for axially reciprocating said nozzles independently and in unison through said can body while the latter is at rest at said station, and means for discharging fluid coating material under pressure in opposed spray jets from said nozzles simultaneously while the nozzles are moving in close axially spaced relation through said can body to effect impingement of said jets against one another and resulting outward deflection thereof in a substantially flat 360° radial spray pattern disposed at right angles to the axes of said nozzle for projection of said pattern against the interior surface of the can body to completely coat the same during unitary travel of said nozzles in one direction relative thereto.

5. Apparatus for interiorly coating can bodies and the like, comprising an intermittently rotatable turret having peripheral pockets for receiving and advancing the cans to a coating station, a pair of horizontal axially aligned and spaced spray nozzles at said station for receiving an open-ended tubular can body therebetween, fluid pressure means for effecting relative axial reciprocation between said nozzles independently and in unison and said can body while the latter is at rest at said station to vary the degree of axial spacing of the nozzles, means for discharging fluid coating material under pressure in opposed spray jets from said nozzles simultaneously while the nozzles are disposed in close axially spaced relation to effect impingement of said jets against one another and outward deflection thereof in a substantially flat 360° radial spray pattern disposed at right angles to the axes of said nozzles for projection of said pattern against the interior surface of the can body to completely coat the same during unitary axial movement of said nozzles relative thereto, means for intermittently rotating said turret, and valve means controlled by said turret rotating means for actuating said coating spray jets and said fluid pressure means in timed relation to the intermittent rotation of said turret.

6. An apparatus for coating interior surfaces of can bodies and the like, comprising a turret having spaced pockets for receiving and supporting can bodies to be coated, means for rotating said turret intermittently to advance said supported can bodies individually into a coating station, a pair of oppositely disposed and movable spray nozzles located at said coating station one on each side of said turret and in axial alignment with the axis of a can body at said station, fluid pressure means connected with each of said nozzles for shifting said nozzles along the axis of a can body at said coating station, rotary valve means connected to said fluid pressure means and to a source of fluid pressure and having ports registerable in sequence to shift one of said nozzles through said can body and into closely adjacent axially aligned relation to the other of said nozzles, then to shift both of said so-aligned nozzles simultaneously back through said can body for a coating operation on said body, and then to return said other nozzle alone back through said body to its original location, means for actuating said valve means in time with the rotation of said turret, and means connected to said nozzles and operable in time with said valve means for discharging a spray jet of coating components from each of said nozzles simultaneously in a direction toward each other while in closely adjacent relation to effect impingement and outward deflection in a substantially flat 360° radial spray pattern disposed at right angles to the axes of said jets for projection against the interior surface of said can body during travel of said nozzles in unison.
